Henry H. Finn

UNITED STATES PATENT OFFICE.

HENRY H. FINN, OF ORONO, MAINE.

HYDRAULIC APPARATUS.

1,132,712.

Specification of Letters Patent. Patented Mar. 23, 1915.

Application filed April 4, 1914. Serial No. 829,679.

To all whom it may concern:

Be it known that I, HENRY H. FINN, a citizen of the United States, residing at Orono, in the county of Penobscot and State of Maine, have invented certain Improvements in Hydraulic Apparatus, of which the following description, in connection with the accompanying drawings, is a specification, like reference characters on the drawings indicating like parts in the several figures.

This invention relates to hydraulic apparatus, and more specifically to combined water motors and pumps.

15 The invention has for its chief object to devise an apparatus of this character in which the energy of a current of water can be utilized to raise automatically a part of the water to a point above the original head.

20 It is a further object of the invention to devise an apparatus of the character indicated which can be economically manufactured, in which wear and deterioration shall be reduced to a minimum, and which will require but little attention while in use.

25 The invention will be readily understood from the following description of one embodiment thereof, reference being made to the figure of the accompanying drawing which shows a central, longitudinal section of an apparatus constructed in accordance with the invention.

30 The apparatus shown comprises a casing 2 which may be made of any convenient number of sections and is designed, when in use, to be set in a vertical position. This casing has a lateral intake opening 4 intermediate of its ends and two discharge passages extending in substantially opposite directions; one, indicated at 6, extending downwardly and the other, indicated at 8, extending upwardly, from the intake opening. A diaphragm 10, projecting from the 35 back of the casing into the intake, serves to direct the greater part of the water entering the intake opening into the lower discharge passage 6 and a smaller part into the upper passage 8.

40 The casing rests upon a skeleton stool, or frame 12, which has several legs of such a height and depth that the space between them is much greater than the cross sectional area of the discharge passage 6 so 45 that abundant room is provided for the flow

of water out of the casing. The framework 12 also includes a central post 14 in the upper end of which is formed a step bearing 16 for a shaft 18 that extends longitudinally through the discharge passages 6 and 8, additional bearings being provided for this shaft in the diaphragm 10 and in the upper end of the casing at 20. For convenience in assembling, this shaft may be made in two sections connected as indicated at 21 by a joint located inside the bearing in the diaphragm.

50 Fast on the shaft 18 and positioned within the lower discharge passage 6 is a water wheel 22 which may be of any suitable construction but, in the form shown, consists of a plurality of blades extending spirally along the shaft 18 and wide enough to fit as snugly within the walls of the discharge passage 6 as possible while providing the necessary clearance. Fast on the shaft 18 in the passage 8 is a rotary pump which may be of any suitable type, but as shown, consists of a plurality of blades 24 similar to the blades 22, but preferably of a lesser pitch and, of course, of a much smaller diameter. The casing above the pump 24 is turned at an angle to provide for the convenient attachment thereto of the pipe or conduit by which the water leaving the pump 55 is to be conducted away.

60 It will now be understood that, when the casing is set in operative position, its intake end being connected to a penstock leading from a suitable head of water, the inflowing current of water will be divided by the diaphragm 10, the greater part of it flowing downwardly through the discharge passage 6 and rotating the wheel 22 at a high rate of speed. A part of the water will be deflected by the diaphragm up through the pump 24 which will be rotated rapidly by the shaft 18, thus lifting water through the pump chamber 8 and forcing it out of the discharge passage above the pump. The 65 shaft 18 will attain such a speed, when the device is operating, that the energy developed by the wheel 22 will be absorbed by the pump 24 in lifting the water.

70 It will be understood, of course, that the dimensions of the casing and pump will be varied in accordance with the particular conditions under which the apparatus is to be operated.

75 Having thus described my invention, what

I claim as new and desire to secure by Letters Patent of the United States is:—

1. In an apparatus of the character described, the combination of a casing having 5 a lateral intake passage and two discharge passages leading from said intake passage in substantially opposite directions, a diaphragm projecting from the back of the casing toward said intake passage and serving 10 to direct water entering the intake passage into the discharge passages, a rotary shaft extending longitudinally through both of said discharge passages and having a bearing in said diaphragm, a water wheel having spiral blades mounted on said shaft in 15 one of said discharge passages and a rotary pump having spiral blades of less pitch than the blades of said water wheel mounted on the shaft in the other discharge passage.
2. In an apparatus of the character described, the combination of a vertical casing having a lateral intake passage, a discharge passage leading downwardly from said intake and a smaller discharge passage leading 25 upwardly from said intake, a diaphragm

extending from the back of the casing toward said intake and serving to direct the water entering the intake into said discharge passages, a stool mounted at the bottom of said casing to support the casing, a 30 thrust bearing in said stool, a shaft extending longitudinally through said discharge passages and having its lower end supported in said thrust bearing, said shaft having bearings in said diaphragm and in the upper part of said casing, a water wheel having spiral blades mounted on said shaft in the lower discharge passage and substantially filling said passage, and a rotary pump having spiral blades mounted on said shaft 40 in the upper discharge passage and substantially filling the latter passage.

In testimony whereof I have signed my name to this specification in the presence of two subscribing witnesses.

HENRY H. FINN.
